JOHN D. SEABERT, OF DAYTON, OHIO, ASSIGNOR TO WESTINGHOUSE ELECTRIC & MANUFACTURING COMPANY, A CORPORATION OF PENNSYLVANIA

ENERGY-TRANSLATING DEVICE

Application filed September 6, 1930. Serial No. 480,174.

My invention relates to energy-translating devices for reproducing sound waves from current at audio frequencies. More particularly, my invention relates to speakers of the cone type and improvements therein for obtaining more efficient reproduction of sound waves.

In the analysis of the operation of speakers of the cone type, more particularly, the diaphragm element, it has been found that, at the higher audio frequencies, the diaphragm does not vibrate as a piston but does vibrate in sections; that is, the whole area of the diaphragm is not effective, whereas, for an efficient reproduction of low-frequency sounds, a radiator of large area must vibrate and with all parts in phase. As the frequency of the impressed current approaches that of the lower audio frequencies, sectional vibration of the diaphragm becomes less pronounced, and the tendency is for the diaphragm to vibrate more and more in the nature of a piston, that is, the diaphragm tends gradually to assume, but never completely, the characteristic of a unitary rigid structure, as the frequency of the impressed wave approaches the lower end of the audio-frequency spectrum.

Insofar as I am acquainted with the prior art, because of the above vibration characteristics assumed by cone diaphragm speakers, no success has been obtained in the radiation of sound of any considerable pressure at frequencies lower than approximately 80 cycles. In speakers of the present day construction, those which are capable of responding to frequencies as low as 80 cycles are considered as having very good frequency-response characteristics. However, to successfully and efficiently reproduce the full effect of instruments emitting notes or tones below 80 cycles, such as the bass of an orchestra or the longer pipes of an organ, it is essential that the speaker be made to respond faithfully to frequencies as low as 25 cycles.

Theory and practice have shown that, in order to radiate sound of long wave lengths, it is essential that a diaphragm of large surface area should be used. For frequencies of the order of 25 or 30 cycles, a diaphragm

having a diameter of approximately 25 to 30 inches will be suitable for the purpose. If a cone of this area were driven at its apex, according to customary practice, only the center portion of the cone would vibrate, and it would be no more effective than possibly a cone having a diameter of 10 to 12 inches. Consequently, merely increasing the size of the cone diaphragm will not produce the results desired.

It is, accordingly, one object of my invention to provide means for extending the low-frequency response of an energy-translating device.

It is another object of my invention to provide means for producing a speaker capable of responding to frequencies of the order of 25 cycles.

Another object of my invention is to provide means for causing the diaphragm of a cone speaker to vibrate as a unit.

In the accompanying drawing, I have disclosed three views of one embodiment of my invention.

Figure 1 is a front view of my device showing the diaphragm structure;

Fig. 2 is a side view, in elevation of my invention;

Fig. 3 is a rear view illustrating the manner of associating the driving units with the diaphragm.

Fig. 4 is a view, in cross-section, along the line IV—IV of Fig. 1.

Fig. 5 is a view, in cross-section, along the line V—V of Fig. 2.

Other objects of my invention will be disclosed in the following description of my device, when taken in conjunction with the above-referred-to drawing.

In order to obtain the piston action of a diaphragm at the low frequencies and to prevent the diaphragm from vibrating sectionally, I have conceived the idea of distributing the driving force about the surface of the diaphragm instead of concentrating it all at one point, such as the apex of the cone diaphragm normally used in practice. To accomplish the above result, I have divided the diaphragm into a plurality of sections and have distributed the driving force

among the various sections of the diaphragm.

Referring more particularly to the drawing, the vibratory element 1 is shown as comprising a plurality of relatively small cone-shaped sections 3, the edges 5 of which intersect in the form of a portion of a hyperbola, as clearly illustrated in Figs. 4 and 5. This particular construction, functioning as trusses to resist distorting forces, adds materially to the strength and rigidity of the diaphragm. The diaphragm is, accordingly, mounted on a frame by means of a flexible edging of leather 7 or other suitable material. Associated with each section, at the apex thereof, is an individual driving unit 9. These driving units are connected electrically from the same source of audio-frequency current and are so connected as to operate in time phase, thereby causing the associated sections of the diaphragm to also operate in the same manner.

A frame or support 11, maintained in spaced relationship to the diaphragm by means of a plurality of bracket arms 13, is employed as a mounting for supporting the driving units 9 in their respective positions with regard to their associated diaphragm sections. The whole assemblage may be mounted upon a stand 15, whereby it may be conveniently moved from one place to another.

The above-described energy translator may be set into a baffle or horn in accordance with present practice in order to realize the full benefit of the device.

Various changes may be made in the structure described by me as comprising one embodiment of my invention. Any driving unit of suitable type may be employed as well as any shaped diaphragm so long as they possess the desired characteristics. Therefore, while I have described my invention in detail, I do not desire to be limited to the details described except insofar as is necessitated by the prior art and the appended claims.

I claim as my invention:

1. An energy-translating device comprising a vibratory element and means for actuating said element as a unit, said means comprising a plurality of independent driving units each associated with a section of said element.

55 2. An energy-translating device comprising a vibratory element possessing a plurality of intersecting sections of substantially cone-shape and driving means for actuating said element by the application of a driving force to the apices of said sections.

60 3. An energy-translating device comprising a vibratory element having a plurality of sections of substantially cone-shape and driving means comprising a plurality of 65 independent driving units associated with

said vibratory element, said driving units being apportioned among said sections.

4. An energy-translating device comprising a vibratory element having a plurality of intersecting sections, the intersections being of such character as to resist distorting forces applied to the vibratory element.

In testimony whereof, I have hereunto subscribed my name this 27th day of August, 1930.
